UNITED STATES PATENT OFFICE.

DONALD V. CONKLIN, OF ALHAMBRA, CALIFORNIA.

ATTACHABLE MATCH BOX.

Application filed January 24, 1927. Serial No. 162,958.

Although my present invention is entitled somewhat broadly, this invention may be understood to relate more particularly to a match box which is provided with means for 5 its removable attachment to a package of cigarettes, or the like.

It being a matter of common observation and experience that unnecessary movements are required in the lighting of a cigarette, by 10 reason of separate searches for packages of cigarettes and for matches, it is an object of my invention to provide an attractive match box with means whereby the same may be releasably, but nevertheless securely, attached 15 to a package of cigarettes, or the like, in such manner that whenever a smoker withdraws his cigarette package from a pocket, his match box will also be at hand.

It is a further object of my invention to 20 provide a removably attachable match box, comprising a leather or other flexible body with sheet-metal or other guard or enclosing frame, a retaining finger or equivalent element being resiliently and/or otherwise relatively removable, and one of said elements 25 being adapted to provide a striking surface for matches.

Other objects of my invention, including 30 the use of a pivoted or sliding plate, or its equivalent, to hold an attached match box to a cigarette package, and including the optional use of a metallic band to hold a flexible flap or flaps or equivalent closure elements in a match protecting-position, may be best appreciated from the following description of 35 an illustrative embodiment thereof, taken in connection with the appended claims and accompanying drawings, in which

Fig. 1 is a side elevational view, showing a 40 match box as attached to a cigarette package, or the like.

Fig. 2 is a top view, taken substantially as indicated by the arrow 2, with a part of a cigarette package broken away.

Fig. 3 is a bottom view, taken substantially 45 as indicated by the arrow 3 of Fig. 1.

Fig. 4 is an edge or an end elevational view, taken substantially as indicated by the arrow 4 of Fig. 1.

Fig. 5 is a detail view, taken substantially 50 as indicated by the line 5—5 of Fig. 4.

Fig. 6 is a perspective view, showing separately a receptacular element such as may be formed of leather or the like and incorporated 55 in a match box such as that illustrated in the preceding figures.

Fig. 7 is a view taken similarly to Fig. 6 but showing a metallic enclosing and attaching device or frame, within which a receptacular element, such as that shown in Fig. 6, 60 may be secured.

Referring to the details of that specific embodiment of my invention chosen for purposes of illustration 11 being a package of cigarettes, or the like, a receptacular element 65 12 (a top opening thereof being shown as provided with side flaps 13, 13', and a front flap 14 and a main cover flap 15) may be secured thereto by means comprising a sheet-metal or similar frame 16 having a relatively 70 movable bottom-engaging slide or lock 17.

The frame 16, in that embodiment illustrated in Fig. 7, will be seen to comprise a back plate 18, an enclosing band 19, a bottom strip 20, a front plate 21, rearwardly projecting 75 side plates 22, 22' and a rebent or dependent retaining finger 23. Unless for the purpose of utilizing bands or scraps of sheet metal, in preference to uniting the mentioned parts of the frame 16 by welding, the entire frame 80 may be advantageously stamped from a slightly resilient sheet metal; and a striking surface may advantageously be provided, as suggested at 24, before or after or incidentally to stamping and/or bending operations suitable to the production of the frame 16 from a 85 flat sheet.

Before attaching the frames 16 to receptacular elements 12, or the like, said frames may be advantageously buffed and/or attractively plated; and the receptacular elements may be secured in place in any suitable manner, as by means of rivets 25, extending through preformed or other openings 26 in the receptacular elements 12 and through registering openings 27, shown as 90 provided in the frames 16.

In order to attach a match box constructed in the described manner to a cigarette package, it will be understood that the finger 23, preferably rather long and somewhat resilient, may be inserted through a top opening 28, in a cigarette package and gently forced downward, but slightly displacing the contained cigarettes, the side plates 22 being kept in engagement with the lateral surfaces of the cigarette package; and that the slideable or pivoted plate 17, or an equivalent lock or latch element, may then be shifted from a retracted position, such as that indicated by the dotted line 17', Fig. 3 to a bottom-engaging position, such as that in which it is 100 105 110

shown in full lines in Figs. 1 and 3; and it may be held in the latter position (guided thereto by a rivet or rivets extending therethrough, or by rebent edges such as are suggested at 29, 29' or by other means) by means such as an engagement between a rivet or boss 30 (provided in the bottom plate 20, or its equivalent) and one of a pair of interfitting openings 31, 31', adapted to be alternately engaged by said rivet or boss.

It will be obvious that attachable match boxes, of the general character described, may be sold either in conjunction with packages of cigarettes or independently thereof; and that, after they are suitably filled with matches, the flaps 13, 13', 14 and/or 15, or as many such flaps or equivalent closure elements as may be preferred, may be normally held down by engagement beneath the band 19, or its equivalent. Thus the smoker of cigarettes has merely to keep track of his cigarette package, the match boxes being always kept attached thereto, except as successive cigarette packages may be employed and replaced; but it should not be overlooked that the receptacular element 12 may itself be formed of sheet-metal and that the band 19, whether attached thereto or to the frame 16, may, if desired, be formed of elastic or other flexible material, or entirely omitted.

Although I have herein described a single complete embodiment of my invention, it should be understood not only that various features of my invention might be independently employed but also that numerous modifications thereof might be devised, by those skilled in the art to which this case relates, without the slightest departure from the spirit and scope of my invention, as the same is indicated above and in the following claims.

I claim as my invention:

1. In an attachable match box: a match receptacular element; a metallic frame secured thereabout; and means for removably securing said frame to a package of cigarettes comprising a back plate carrying an outwardly and downwardly dependent finger and rearwardly bent side plates.
2. In an attachable match box: a match receptacular element; a metallic frame secured thereabout; and means for removably

securing said frame to a package of cigarettes, said frame comprising a bottom plate which is integral with a front plate and to which is movably secured a latch or lock element, shiftable to a position beneath a cigarette package.

3. In an attachable match box: a match receptacular element; a metallic frame secured thereabout; and means for removably securing said frame to a package of cigarettes, said frame comprising a back plate carrying an encircling band and a dependent finger, extending outwardly and downwardly from said element supporting frame and side plates; and in which a bottom plate is integral with a front plate and is provided with a locking element which is shiftable to and from a package-engaging position.

4. In an attachable match box: a match receptacular element; a metallic frame secured thereabout; and means for removably securing said frame to a package of cigarettes, said frame comprising a back plate carrying an encircling band and a dependent finger extending outwardly and downwardly from said element supporting frame and side plates; and in which a bottom plate is integral with a front plate and is provided with a locking element which is shiftable to and from a package-engaging position,—said front plate being provided with a striking surface.

5. In an attachable match box: a match receptacular element; a metallic frame secured thereabout; and means for removably securing said frame to a package of cigarettes, said frame comprising a back plate carrying an encircling band and a dependent finger extending outwardly and downwardly from said element supporting frame and side plates; and in which a bottom plate is integral with a front plate and is provided with a locking element which is shiftable to and from a package-engaging position,—said front plate being provided with a striking surface and said receptacular element being provided with a flap which is engageable beneath said band.

In testimony whereof, I have hereunto set my hand at Los Angeles, California, this 18th day of January, 1927.

DONALD V. CONKLIN.
